(57) **CLAIM**

The ornamental design for a dual-tip highlighter, as shown and described.

DESCRIPTION

FIG. 1 is an upper front right perspective view of a dual-tip highlighter showing my new design;

FIG. 2 is an exploded upper front right perspective view of the dual-tip highlighter shown in FIG. 1;

FIG. 3 is a left side elevation view of the dual-tip highlighter shown in FIG. 1;

FIG. 4 is a top plan view thereof;

FIG. 5 is a front elevation view thereof;

FIG. 6 is a right side elevation view thereof;

FIG. 7 is a bottom plan view thereof;

FIG. 8 is a rear elevation view thereof;

FIG. 9 is an upper front right perspective view thereof with the lower cap removed and not shown for convenience of illustration; and,

FIG. 10 is an upper front right perspective view thereof with the upper cap removed and not shown for convenience of illustration.
